UNITED STATES PATENT OFFICE.

FREDRIK SELMER, OF CHRISTIANIA, NORWAY.

METHOD OF CASTING HOLLOW CONCRETE MASONRY.

Application filed May 7, 1923. Serial No. 637,321.

To all whom it may concern:

Be it known that I, Ingenieur FREDRIK SELMER, of Hausmannsgt. 34, Christiania, Norway, a subject of the King of Norway, have invented certain new and useful Improvements in Methods of Casting Hollow Concrete Masonry; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to a method of casting hollow concrete masonry, especially the outer walls of buildings, and has for its purpose to provide a cheap and efficient interconnection between the inner and outer walls of said masonry. This object is attained by the use of interconnecting members as reinforced concrete braces or stays (diagonal stays, cross stays), which are cast and hardened beforehand in a concrete casting plant. These interconnecting members are then with their ends cast into the inner and outer walls, in the usual way by the aid of molds.

In this manner it is possible to undertake the comparatively difficult and complicated casting of the braces or stays in a plant suited for such manufacture, thereby simplifying the erection of the walls on the building site, where it is only necessary to cast the inner and outer walls in the usual way, and insert the ends of the braces or stays in the respective walls.

In the accompanying drawings are shown various forms of masonry erected in accordance with this method, in which

Fig. 1 is a vertical section through a hollow wall provided with diagonal stays,

Fig. 2 is a corresponding section of a wall provided with cross stays,

Fig. 3 is a modification of the form shown in Fig. 2, and

Fig. 4 is a vertical section showing besides the vertical stay system also a similar horizontal stay system.

In Fig. 1, 1 is the outer- and 2 the inner wall of the masonry. These walls are in well known manner cast by the aid of mold plates or sections (not shown). According to my invention I insert as the casting progresses diagonal cement stays 3 provided

with a reinforcement 4 (indicated in dotted lines). The end part of these stays inserted in the walls is suitably made of the same width as these walls, and the ends 60 may suitably be provided with horizontal holes 5 for the insertion of the horizontal rods of the inner and outer walls respectively. As will be seen from the drawings the rod 4 extends around these holes 5 so as 65 to establish a secure connection between the rods of the inner and outer walls, said connections transmitting tensions and pressures direct from the horizontal rods of the one wall to the other. The invention is, however, not limited to this use of holes in the stays or braces 3 for the bracing of the walls.

In Fig. 2 there is used instead of the diagonal stays 3 cross stays 7 provided with crossed reinforcements 8 (shown in dotted lines). According to Fig. 3 the method differs from that of Fig. 2 only therein, that the cross stays 7 are not placed directly adjoining each other, but are placed at suitable intervals, said intervals preferably corresponding to the height of a scaffolding plate. In this figure there is also illustrated the use of vertical ribs 9 and 10 respectively, along the vertical planes in which the cross stays are placed. This is a particularly suitable form for the method.

In the modification illustrated in Fig. 4 vertically placed diagonal stays 3 are used corresponding to those of Fig. 1, and also 90 horizontal stays 12 are inserted, which may be of the same form as the stays 3 or of any other suitable form.

By the above method there is formed a kind of lattice-work or frame-work girder 95 construction between the inner and outer walls, whereby an efficient interconnection between the outer and inner side of the wall is provided.

I claim:

1. A method of casting hollow concrete masonry which consists in the successive steps of arranging in a mold reinforced concrete stay members having laterally extending end portions provided with perforations; inserting reinforcing rods through the perforations of said end portions; and casting the inner and outer walls around said end portions and said reinforcing rods, whereby the total width of the hollow masonry is determined by the lateral distance between the outer faces of the end portions.

2. A method of casting hollow concrete masonry which consists in the successive steps of arranging in a scaffold reinforced concrete stay members having laterally extending end portions provided with perforations; inserting reinforcing rods through the perforations of said end portions; and casting the inner and outer walls around said end portions and said reinforcing rods,
5 whereby the total width of the hollow masonry is determined by the lateral distance
10

between the outer faces of the end portions, and the outer face of the walls will be flush with the outer ends of the end portions.

In testimony that I claim the foregoing ¹⁵ as my invention, I have signed my name in presence of two subscribing witnesses.

FREDRIK SELMER.
